PICKUP TRUCK MOUNTED ROPING SADDLE

Thurman J. McLeish, P.O. Box 143,
Dighton, Kans. 67839

Filed May 23, 1966, Ser. No. 2,411

Term of patent 14 years

(Cl. D38—15)

FIG. 1 is a top perspective view of a pickup truck mounted roping saddle showing my new design;

FIG. 2 is a side elevational view thereof, the broken line showing of the pickup truck being for illustrative purposes only;

FIG. 3 is a bottom plan view thereof; and

FIG. 4 is a rear elevational view, portions of the saddle having been omitted for convenience of illustration.

The dominant features of the design reside in the full line portions on the drawing.

I claim:

The ornamental design for a pickup truck mounted roping saddle, as shown and described.
